PORTABLE CAR COOLER

Walter C. Phillips, San Francisco, Calif., assignor
to Phillips Refrigeration Products, Inc., San
Francisco, Calif., a corporation of California

Application October 17, 1931, Serial No. 569,479

6 Claims. (Cl. 98—6)

My invention relates to means for controlling the temperature in transports such as refrigerator cars and is particularly designed to facilitate and accelerate the process of cooling.

It is in general, the present practice in refrigerator cars to construct the cars with one or more compartments for containing a refrigerant, usually ice, and to load the cars with fruits or produce in the presence of the ice in order to maintain the car temperature at a low enough point to preserve the contents thereof. The cooling of such cars to reduce the temperature from normal atmospheric temperature to a sufficiently low value is at present a relatively slow process, depending primarily upon natural circulation of air contacting at one point in its cycle with a refrigerant.

It is an object of my invention to provide means for accelerating the cooling of a refrigerator car or other similar container.

Another object of my invention is to provide means for forcibly circulating air within such a car.

Another object of my invention is to provide a device which can be mounted in any one of various different sized refrigerator cars, in order to force a circulation of air therein.

The foregoing and other objects are attained in the embodiment of the invention shown in the drawings, in which

Figure 1 is a transverse section of the upper portion of a typical refrigerator car, portions being broken away to reduce the size of the figure and showing installed therein a car cooler in accordance with my invention.

Figure 2 is a cross section, the plane of which is indicated by the lines 2—2 of Figure 1.

Figure 3 is a cross section, the plane of which is indicated by the lines 3—3 of Figure 1.

Figure 4 is an elevation of a clamping device for use on the end plate of my device, a portion of the handle being in section to increase the clarity of the disclosure.

In its preferred form, the car cooler of my invention is for use in a refrigerator car having a bulkhead extending between the walls of the car and spaced from the ceiling thereof to provide an opening and comprises a closure having an aperture therein and adapted to be positioned adjacent the opening and supported by the car for sealing the opening and designed to carry a fan for effecting a flow of air through the aperture in the closure.

Although the car cooler of my invention is adapted for use in various different environments

and is susceptible to variations in structure in accordance with the environment in which it is used, it finds a field of usefulness in connection with a refrigerator car such as is shown in the drawings and which includes a pair of walls 7 and 8 extending from the floor 9 of the car to the ceiling 11 thereof. It is customary for such a car to be divided into at least two different compartments 12 and 13 which are separated by a bulkhead 14 extending nearly to the floor 9 but slightly spaced therefrom to permit the flow of air between the compartments 12 and 13 under the bulkhead 14 and likewise spaced from the ceiling 11 to provide an opening 16 through which air can circulate between the compartments 12 and 13 15 above the bulkhead 14.

In different refrigerator cars, the distance between the side walls 7 and 8 varies considerably as does the size of the opening 16 between the top of the bulkhead 14 and the ceiling 11. It is usual for the compartment 13 to be equipped to receive blocks of ice 17 or any other suitable refrigerant and for the compartments 12 to receive produce or other perishable material, disclosed in Figure 1 as being contained in a plurality of boxes 18. 25

In order to provide a closure which will effectively seal the opening between the bulkhead 14 and the ceiling 11 in order to provide a confined path for air flowing between the compartments 12 and 13, I preferably afford a pair of end plates 30 21 and 22 which are similar and each of which is preferably constructed of a sheet 23 of metal or other suitable material provided adjacent its upper edge with any suitable sealing means 24, and adjacent its upper lateral edge is provided with 35 a spike 26 or a similar element adapted to engage with the material of the wall 7 in order to assist in holding the plate 21 in place.

The bottom of the plate 21 is preferably supported on a strip 27 or batten conveniently fabricated of wood and provided with a protective sheathing of metal 28. The batten or strip 27 is held in place by one or more hooked bolts 29 passing through suitable bores in the strip 27 and provided with wing nuts 31 in order to adjust the 40 position of the strip with respect to the upper edge of the bulkhead 14 over which a hook 32 at the opposite extremity of the bolt 29 is engaged. By suitably positioning the wing nuts 31 the 45 height of the strip 27 with regard to its distance from the ceiling 11 and from the upper edge of the bulkhead 14 can readily be adjusted. To facilitate its engagement with the strip 27 the 50 lower end of the plate 21 is provided with an 55

angular extension 33 which conforms in contour with the surface of the strip 27.

In mounting the plates 21 and 22 their lower edges or extensions 33 are positioned over the previously mounted and adjusted strip 27 and the spikes 26 are thrust into the material of the side walls 7 and 8 with the upper edge 24 in tight engagement with the ceiling 11 of the car.

To complete the closure of the space between the bulkhead and the ceiling remaining after the two plates 21 and 22 have been positioned, I provide a center plate 36 which is preferably constructed of metal or another suitable material and is in many respects similar to the end plates 21 and 22. The center plate 36 is provided along its lower edge with an angular extension 37 adapted to interengage with the strip 27 and to be supported thereon, while along its upper edge, it is provided with a packing strip 38 intended to abut the ceiling 11 of the car. Since the distance between the side walls 7 and 8 in various cars varies considerably, the center plate 36 is constructed of sufficient length to overlap the end plates 21 and 22 more or less depending upon the distance to be spanned. In order to effect a tight closure the center plate is extended by strips 39 and 41 which overlap the end plates 21 and 22 so that the major portion of the center plate is co-planar with the end plates 21 and 22.

The upper edge of the center plate is retained in any adjusted position by means of one or more toggle mechanisms 42, which are provided with spikes 43 designed to penetrate the material of the ceiling 11 in any adjusted position of the center plate. The spikes 43 project from a block 44 having projecting bolts 48 slideable in slots 45 in a channel frame 46 secured to the center plate 36. The block is actuated by movement of a toggle lever 47, one end of which is fastened to the block 44 by one of the bolts 48 and to which is fastened a pair of links 49 by a pivotal connection 51. The other end of the links is connected to a relatively stationary block 52 adjustably confined in the channel 46 by means of a pin 53. When the lever or handle 47 is in the position shown in dotted lines in Figure 3, the spikes 43 are retracted and are disengaged from the ceiling 11 while when the handle is in the full line position, as shown in Figure 3, the spikes 43 are projected into engagement with the ceiling 11 in order to hold the center plates 36 in position.

Formed as part of the central plate 36 is a conduit 56 which bounds a central aperture in the plate and which is extended to a circular reinforcing collar 57 to which a cylindrical shell 58 is secured by any suitable means. A bracket 59 mounted on the shell 58, serves as a support for an electric motor 61 or any other suitable driving means for a fan 62 which is designed to effect a flow of air through the aperture in the central plate 36 and from one compartment 12 to another compartment 13, or in the opposite direction. In order to make the fan reversible so that the flow of air can be altered in direction as desired, the shell 58 is likewise provided with a ring 63 comparable to the ring 57 and designed to be secured thereto by the same fastening means. By virtue of this expedient, the manner of positioning the central shell 58 on the extension 56 governs the direction of air flow between the compartments 12 and 13.

It is usually desirable to provide means for preventing the passage of large particles of debris and similar matter, and for that reason I preferably affix to the shell 58 an additional frame 64

which is of annular form and over the open end of which is positioned a screen 66 or other suitable filter.

When the cooling of the interior of a car of the refrigerator type is to be accelerated and carefully controlled in accordance with my invention, the compartment 13 is filled with ice or other suitable refrigerant, the strip 27 is adjustably mounted in place in accordance with the general contour and relationship of the bulkhead in the car, the end plates 21 and 22 are placed in position and are held by the spikes 26, the center plate 36 is then mounted in juxtaposition and the toggle handles 47 are operated to secure the central plate in position to complete the closure of the opening between the compartments 12 and 13. The motor shell 58 is then mounted in position in accordance with the direction of desired air flow and subsequently, the screen frame 64 is fastened in place. When electric current is furnished to the motor 61 the fan 62 rotates effecting a forced circulation of air from the compartment 12 through the fan itself and through the aperture in the center plate 36 and over the refrigerant such as ice 17 in compartment 13, the air circuit being completed by flow beneath the bulkhead 14 back to the compartment 12. If, however, the direction of fan rotation should be reversed, air is drawn from the compartment 12 beneath the bulkhead 14 over the refrigerant 17 and is expelled through the aperture in the center plate 36 and is directed outwardly through the screen 66 into the compartment 12 for recirculation.

By use of the car cooler of my invention it is feasible to control the temperature of a refrigerator car very exactly and to reduce materially the time required to lower the temperature from its atmospheric value to the desired degree for the storage of perishable goods in the car. The cooler, after serving its purpose in reducing the temperature of the car can very quickly be detached and can as quickly be set up again in another car even though the second car is of different size and of different relationship of parts.

It is to be understood that I do not limit myself to the form of the car cooler shown and described herein, as the invention, as set forth in the following claims may be embodied in a plurality of forms.

I claim:

1. An air circulator for use in a car having a bulkhead bounding an opening between different compartments in said car comprising a closure having an aperture therein and adapted to overlie said opening, a support for said closure adjacent said bulkhead, a circulating fan mounted on said closure for circulating air through said aperture, and means for wedging said closure between said support and the ceiling of said car.

2. An air circulator for use in a car having a bulkhead comprising a supporting strip, means for adjustably supporting said strip against said bulkhead, a closure having an aperture therein resting on said strip, and means on said closure for effecting a flow of air through said aperture.

3. An air circulator for use in a car having walls, a ceiling, and a bulkhead extending between said walls and spaced from said ceiling to provide an opening, comprising a supporting strip, means for adjustably supporting said strip on said bulkhead, a pair of end plates each adapted to rest on said strip and to abut one of said walls and said ceiling to seal a portion of said opening, a center plate adapted to rest on said strip and engage said

ceiling and to overlap said end plates to seal the remainder of said opening, and means mounted on said center plate for effecting a flow of air from one side of said bulkhead to the other side thereof.

5. An air circulator for use in a car having a bulkhead bounding an opening between different compartments in said car comprising a closure having an aperture therein and adapted to overlie said opening, means on said closure for effecting a flow of air through said aperture, means for supporting said closure at any selected inclination, and means on said closure and adapted releasably to engage said car for holding said closure at any 10 selected inclination.
10. An air circulator for use in a car having a

bulkhead, comprising a strip transversely spanning said car, means for supporting said strip adjacent said bulkhead, a closure demountably supported on said strip, said closure having an aperture therein, and means on said closure for effecting a flow of air through said aperture.

15. An air circulator for use with a refrigerator car having a refrigerant compartment and a load compartment, comprising a support transversely spanning said car adjacent the junction of said compartments, a closure incorporating an air circulator resting on but removable from said support, and means engaging said car for maintaining said closure in a selected position upon said support.

WALTER C. PHILLIPS.
